UNITED STATES PATENT OFFICE.

GOTTLOB HÄNDLE, OF MÜHLACKER, GERMANY.

CHARGING DEVICE FOR MIXING AND CRUSHING MACHINES.

964,512.

Specification of Letters Patent. Patented July 19, 1910.

Application filed February 6, 1908. Serial No. 414,549.

To all whom it may concern:

Be it known that I, GOTTLÖB HÄNDLE, a subject of the German Emperor, and resident of Mühlacker, Kingdom of Würtemberg, Germany, have invented Improvements in and Relating to Charging Devices for Mixing and Crushing Machines, of which the following is a specification.

The present invention relates to a charging device for mixing and crushing machines, particularly for those used in the brick industry. The machine is provided with a cutting and mixing apparatus.

The object of the invention is to provide a continuous and simultaneous supply of various materials separate from one another to the machine, to cut off from the material by means of the cutting drum fine flat strips which are thrown in all directions by said drum so that the ingredients thereof are thoroughly mixed, and further to construct the feeding apparatus in such a manner as to reduce to a minimum the friction between the walls of the feeding apparatus and the material.

The device differs from the known charging devices, principally in the provision of the feeding apparatus consisting of a casing, the side walls of which possess a trapezoidal shape in longitudinal as well as in cross section, while vertical partitions in said casing are provided to separate the different materials, the purpose aimed at being the greatest possible reduction of friction between said materials and the aforementioned walls.

In the drawings in the several figures of which similar characters designate like parts:—Figure 1 is a longitudinal section of a device embodying my invention. Fig. 2 is a ground plan of the charging device. Fig. 3 is a cross section of the same. Fig. 4 represents the cutting drum in section.

The charging device consists of the well known horizontal endless feeding band *a* located below a hopper 1 having the side walls *b*, *c* which are made from sheet metal or other suitable material which is rigid. The side walls *b*, *c* are arranged so that they approach one another from the bottom toward the top and from the front to the rear end, whereby the feeding apparatus has a trapezoidal shape in longitudinal section as well as in cross section. It therefore follows that the different materials *e*, *f*, *g* which fall ver-

tically from the several compartments of the hopper, which are formed therein by vertical partitions on the endless band *a* owing to gravity, and which are moved forward by means of said feeding band, are gradually removed from the side walls in both, vertical and horizontal directions, so that the friction between the materials and the side walls is greatly diminished and reduced to a minimum. The said materials can be fed into the device through funnels or in any other suitable manner, no device for this purpose being shown in the drawing, as such device does not form part of the present invention.

At the lower ends of the vertical partitions *h*, *i*, *k* which separate the different materials, vertically adjustable gates *l*, *m*, *n* are provided, which permit the deposit of the materials to be mixed on the band *a* in the desired proportions and one above the other.

At the front end of the device the cutting drum *o* is revolubly mounted upon axle *p* suitably journaled in the side walls *b*, and *c*. This drum *o* has cutters *q*, *r*, *s*, which are alternately mounted in such a manner that they cut off flat fine strips from the materials which are fed to the drum by the endless band *a*. Said strips are thrown in all directions by the cutters so that the materials are intimately mixed.

As will be seen in Fig. 4, each of the cutters has a yielding contact with the material due to the spring *t*, which is secured to the drum *o*, and bears against the back of the cutter.

The knives *s* consist of straight blades preferably of the shape shown in Figs. 1 and 4, while the knives *r* are formed with right angular projecting pieces (Fig. 2) which have a chisel like effect and cut thin fine flat strips off the material, said strips being cut into pieces and scattered in different directions by the knives *s*.

Having fully described my invention, what I claim and desire to secure by Letters Patent is:—

A charging device for mixing and crushing machines, comprising in combination, with an endless feeding band, a hopper formed of two side walls and slanting both in vertical and in horizontal direction, and vertical partitions for separating the different materials having adjustable gates at

2
their lower ends for regulating the quantity of materials to be deposited upon said endless band, and a cutting drum at the front end of the charging device having alternating cutters for cutting fine flat strips off the materials and intimately mixing the same, substantially as described and shown.

In witness whereof I have hereunto set my hand in presence of two subscribing witnesses.

GOTTLOB HÄNDLE.
